UNITED STATES PATENT OFFICE.

LYELL T. TERWILLIGER, OF MELROSE, MASSACHUSETTS.

HEATING APPARATUS.

SPECIFICATION forming part of Letters Patent No. 252,064, dated January 10, 1882.

Application filed April 30, 1881. (No model.)

To all whom it may concern:

Be it known that I, LYELL T. TERWILLIGER, a citizen of the United States, residing at Melrose, in the county of Middlesex and State of Massachusetts, have invented certain new and useful Improvements in Heating Apparatus; and I do hereby declare that the same are fully described in the following specification and illustrated in the accompanying drawings.

- 10 This invention relates to heating apparatus of all kinds, and embodies a new system of drafts, having the air admitted to the top of the fuel, and the openings into the flues at or below the fire-level and near the horizontal 15 plane of the supporting grate, whereby the smoke, gases, and other products of combustion are carried downward through the fire, or consumed in their passage and utilized as fuel, while the air for respiration is received 20 from the bottom into an adjoining or surrounding air chamber, in which it is heated as it rises in contact with the radiating-surface of the flue, and flows thence through the registers into the room or through pipes to other 25 rooms. The upper part of the fire-pot of a furnace constructed according to my invention is therefore kept comparatively cool, and the lower part of the wall of the radiator is heated to a high degree, and forms a radiating-surface 30 adapted to raise rapidly the temperature of the air in contact with it in the adjoining air-chamber. The lowest and coldest air is therefore heated first and most, because of the direct draft downwardly or laterally from the 35 fire to the lower part of the radiator. The intensity of the heat is expended on the radiating-surface which heats the lower stratum of air, rather than principally upon the fire-pot and the upper part of the radiator. The smoke is 40 consumed, together with the deleterious gases, by being brought into contact with the incandescent coal, and the escape of cinders and unburned particles is precluded. Consequently 45 the fuel is utilized to the utmost, and much of the annoyance arising from the use of coal as fuel is done away with. At the same time simplicity and economy of construction are adhered to.

A removable grating may be employed to 50 shield the inlets to the flues, which at the bottoms are made sloping to be self-cleaning

of ashes or other deposits, and to give an upward tendency to the draft after entering them. Doors may be provided below the grate for access to the base of the flues.

I am aware that it is not broadly new to consume smoke and gases by a downward draft through the fire; and I claim this feature only when employed in connection with the adjoining or surrounding air-heating passages, through 55 which the air to be heated is caused to ascend in contact with the radiator-wall, heated principally at its base by the downward, outward, and upward current from the fire, as herein described.

The annexed drawings illustrate my invention as applied to a portable furnace and to an open grate or fire-place heater, Figures 1, 2, and 3 being partly in section to show the details of construction; but it is obvious the details may be varied without departing from my invention, and also that the principle involved is applicable, with minor modifications, to other forms of heating apparatus. Figs. 4, 5, and 6 show certain of the parts detached.

Referring to the portable furnace shown in Fig. 1, A is the fire-grate, upon which rests the body of fuel B, surrounded by the fire-pot C. D is the door through which the coal is introduced and the air admitted to maintain combustion, an adjustable slide, E, permitting control of the air-current.

F F are flue openings or inlets to the annular flue or smoke-chamber F', such openings being at or below the fire-level, so that the 85 air current or draft is, as denoted by the arrows, downwardly through the body of fuel, and through the grate A and flue-openings F into the smoke-space F' between the fire-pot and the radiator G, thence upwardly to the top of 90 the fire-chamber H and into the escape-pipe I. An opening from the fire-pot direct, which may be used in starting a fire, is indicated by dotted lines at H'.

The radiator G is made heaviest in its lower portion to withstand the extreme heat of the caloric current from the fire directly against such part, which may be made of soapstone, terra-cotta, cast-iron, or other suitable material. Cold air is admitted to the air-chamber 100 J at suitable points in the bottom of the furnace and comes into contact with the hottest

part of the radiator, thence rising to the distributing-pipes K.

L represents the double outer wall of the furnace.

5 The grate A should be coarse and of the best material to withstand extreme heat, and is preferably made, as shown, with hollow bars, admitting a current of cold air to pass through them into the flue, and by absorbing heat from the bars serving to some extent to keep them cool and to prolong their usefulness. I also contemplate passing a water-current through the grate-bars, that they may be cooled and the water heated, in which case suitable connections at each end are required and proper pressure to insure circulation.

The inlets to the flue F' are made oblique, about as shown, so as to be self-cleaning of ashes and the like. Efficient means of shaking or raking the grate should also be provided to prevent clogging the draft.

20 The fire-place heater illustrated in Fig. 2 will be readily understood. The fire is guarded in front by a fender, M, fitting closely to the 25 grate, and furnished with a removable lower central portion, M', to check the draft and to remove for taking up the ashes. The draft is downwardly and laterally through the fuel and through the bottom and sides of the hanging 30 grate H, which is made sloping at its sides to be self-cleaning, and with an open space between it and the adjacent flue-opening at each side of the fire to facilitate the draft.

35 The bottom of the flue F is sloped sharply for the purpose explained in connection with the similar construction in Fig. 1. The flues terminate in the chimney, entering it one from each side of the fire. The walls of the flues form radiators. Those next to the fire radiate 40 into the room direct, while the other walls correspond to the radiator G of Fig. 1, and heat the air-current entering from below and ascending through the air-chambers J to discharge through suitable registers, R, or to be 45 carried up in pipes K to the rooms above. The grate-bars may likewise be fitted for the circulation of an air or water current.

Fig. 3 shows broken away a furnace of the same general construction as is shown in Fig.

50 1. The draft is, however, down through the fuel, and thence laterally and upwardly through oblique openings F in or between the fire-brick C and into the flue or smoke-chamber F'. The oblique character of the openings serves to 55 keep them free from ashes or fragments of coal and gives an upward tendency to the caloric current.

Fig. 4 shows two forms of the recessed fire-brick detached.

If desired, a grating or fender may be employed as an additional protection against clogging the openings F. One form of such a device is indicated at S in Fig. 3, and a quarter-section of the same in Fig. 5.

60 Where the grates are made hollow for circulation of air, as described, I form them in two parts, each about as represented in Fig. 6, and unite them by rivets; or they may be cast in one by coring.

65 The furnace fire-pots and adjacent parts are shown as supported on uprights U, rising from the base of the radiator; but such supports may consist of lateral lugs or ledges extending inwardly at intervals from the radiator; or they may be otherwise arranged as is most convenient.

70 I claim as of my invention—

1. A heating apparatus consisting of the following elements arranged in the order shown and described, viz: a central fire-pot through 80 which a downward draft is maintained, a smoke chamber or passage for the heated products of combustion at each side of said fire-pot and opening from the base thereof, and a hot-air chamber outside of said smoke-chamber and 85 separated therefrom by the radiator G, which receives at its base the direct caloric-current, whereby the air for respiration is warmed in passing upwardly, substantially as set forth.

2. A heating apparatus constructed, as described and shown, with oblique openings extending upwardly and outwardly from the base of the fire-pot, smoke-flues ascending therefrom, and an air-chamber outside said flues, adapted to be heated by the radiator which 95 separates the flue from the air-chamber, substantially as set forth.

3. An open grate or fire-place having a central open fire-pot, a flue at each side thereof, adapted to receive the products of combustion 100 at or below the fire-pot level and communicating with the chimney, and a hollow column adjoining each flue and provided with a cold-air inlet at its bottom and one or more hot-air pipes at top, substantially as and for the purpose set forth.

105 In testimony whereof I affix my signature in presence of two witnesses.

LYELL T. TERWILLIGER.
